CLAIM

The ornamental design for a pharmaceutical tablet, as shown and described.

DESCRIPTION

FIG. 1 is a top, side, front perspective view of a pharmaceutical tablet showing my design;
FIG. 2 is a front elevational view thereof, the rear elevational view is identical to the upside-down view of FIG. 2;
FIG. 3 is a top plan view thereof, the bottom view being a mirror image of that shown; and,
FIG. 4 is a side elevation view thereof, the opposite side being a mirror image of that shown.

1 Claim, 1 Drawing Sheet*FIG. 1.*

FIG. 2.

FIG. 3.

FIG. 4.
